UNITED STATES PATENT OFFICE.

JOHN F. ROBB, OF CLEVELAND HEIGHTS, OHIO, ASSIGNOR, BY MESNE ASSIGNMENTS, TO KOEHRING COMPANY, OF MILWAUKEE, WISCONSIN, A CORPORATION OF WISCONSIN.

MACHINE FOR CONSTRUCTING REINFORCED-CONCRETE ROADS.

Application filed March 22, 1921. Serial No. 454,535.

To all whom it may concern:

Be it known I, JOHN F. ROBB, a citizen of the United States, residing at Cleveland Heights, in the county of Cuyahoga and State of Ohio, have invented certain new and useful Improvements in Machines for Constructing Reinforced-Concrete Roads (Case No. 1), of which the following is a specification.

With a view to reducing to a minimum the longitudinal cracking of concrete roads which are being used very largely today for the purposes of road construction, engineers are requiring the employment of reinforcement for the concrete. In practice it has been found that the use of metal reinforcing for road construction is advantageous for maintaining the road in a condition of highest efficiency, and to eliminate the defective cracking or breaking of the road which in times past has created considerable objection thereto for obvious reasons.

In so far as I am aware, the roads which have been built more or less recently with reinforcement embodied therein, have been constructed by depositing a base layer or section of concrete, placing thereon by manual labor a section of metal reinforcing, and then depositing upon the reinforcing and base layer of concrete a surface layer of concrete which unites with the base layer in the well known manner.

The use of manual labor in handling the metal reinforcing for the road is something desired to be obviated in the practical embodiment of my present invention. With the foregoing object in view I have designed a machine which is capable of mechanically handling the metal reinforcing, whether the same be used in sections of predetermined size, or unreeled from a bale of suitable dimensions to properly correspond with the requirements of the road dimensions.

My machine takes a number of different embodiments in practice. In one instance it may be combined as a part of the paver of the type generally shown in United States patent to Lichtenberg No. 1,141,470, issued June 1, 1915. According to this construction, the reinforcement handling machine would progress with the paving machine by

which the concrete is distributed, and I utilize the paving machine as a crane for performing certain preliminary operations of getting the reinforcing material into position ready to be dispensed by the machine provided for this purpose.

A further embodiment of the machine of the invention is to design the same as a self-contained power driven machine adapted to travel upon the road forms as rails, and equipped with suitable pulling devices to pull the reinforcing into place upon the base section of concrete, which is of course laid previous to the placing of the reinforcement, in position for use. If the reinforcement is handled in bales I contemplate the utilization of suitable straightening means therefor, together with cutting devices by which the reinforcing is cut in proper lengths to be laid down upon the base section or layer of concrete, preliminary to the distributing thereon of the surface layer or section.

My invention may take other forms than those illustrated for the purposes of giving a general idea of the scope and usefulness thereof, in this specification, and in the annexed drawings.

Figure 1 is a plan view showing a road in process of construction, an industrial railway at one side thereof for the supplying of materials, a paving machine by which the concrete is mixed and distributed, and the way in which the reinforcement in flat sheets may be supplied to the site where it is to be used;

Figure 2 is a perspective view showing the end portion of the boom of the paver, and a quantity of reinforcing sheets supported by a platform and illustrated as when being lifted by the boom acting as a sort of derrick, to shift the reinforcing material from one side of the road into a position in which it is supported on the carrier of the dispensing machine;

Figure 3 is a plan view of the platform and suspension cables as shown in Figure 2;

Figure 4 is a side view of the machine shown in Figure 1;

Figure 5 is a plan view of the reinforcement dispensing machine showing more

clearly the manner in which the pull cables are connected to pull a section of reenforcement into place upon the site where it is to be used;

5 Figures 6 and 7 are modified adaptations of the invention being shown in side elevation and section, respectively;

10 Figure 8 is a view showing more clearly the shearing knives for cutting the reenforcement sections from the bale when the reenforcement is supplied in bales for the dispensing machine.

15 Generally speaking, the machines of the invention in their various embodiments are rather simple in construction. In so far as the reenforcement dispensing mechanism is concerned, the same is mounted upon a carrier capable of operating on the road forms at opposite sides of the road, as rails.

20 This carrier supports the sheets of reenforcing when they come flat, or it is constructed to support the reenforcement in a bale, if the baled type of this fabric is utilized.

25 With the above general statement reference is made to Figures 1 and 4 particularly, in which A denotes generally a partially illustrated machine of the type of the previously identified Lichtenberg patent. This 30 machine has a boom B on which traverses the distributing bucket C. The machine A operates on the subgrade 1, or over said subgrade, as desired, and progresses in the direction of the arrow in the road building 35 operation. In rear of said machine is the metal reenforcement dispensing mechanism which comprises a carrier 2 having wheels 3 adapted to travel on the road forms 4 which act as rails under these conditions.

40 At its rear end carrier 2 is adapted to support the platform 5 on which the reenforcement arranged in superposed sheets or sections of required size is disposed. The front portion of the carrier 2 is largely an open 45 frame as shown in Figure 5. The paving machine A is equipped with a special winding drum 6, power driven, like the other driven operating devices of said machine, from the engine with which the machine A

50 is equipped. Suitable draft connections are provided between the rear end of the truck of the machine A and the front end of the carrier 2. A pull cable 8, to which the pulling hooks 9 (see Figure 5) are attached 55 is adapted to wind about the drum 6 on the machine A, and unwind therefrom. The hooks 9 are adapted to be engaged with the front edge of the top section of the metal reenforcement on the carrier platform 5, said reenforcement being designated 10. The operator of the machine A then causes 60 the drum 6 to be driven and the said engaged sheet of reenforcement 10 is pulled into place upon the base layer of concrete, designated 11, which has been previously 65

disposed upon the subgrade 1. The length of the carrier 2 may be as desired so that several sections of the reenforcement 10 may be pulled into position at a time.

To facilitate the placing of a large quantity of reenforcement 10 upon the carrier 5, I preferably modify the construction of the paver A to render the boom B thereof a sort of crane or derrick device. In other words, I utilize a power driven drum 12 on the upper part of the frame work to actuate the cable 13 for raising the boom B. I utilize also a power driven gear 14 to operate the worm shaft 15 by which the worm gear 16 fixed to the vertical axis of the boom B, may be operated, to shift said boom in a horizontal plane.

With the above described controlling means it is evident that when a quantity of the reenforcement 10 is at one side of the 85 road, as shown in Figure 1, a hook 17 on the end of the boom B may be engaged with the suspension cables 18 of the platform 5 and said platform and reenforcement may be lifted, carried laterally, and readily 90 placed in position on the carrier 2. The hook 17 is swivelled on the boom B.

If desired, the sides of the carrier 2 may have depending brackets 19 of an adjustable type to assist in supporting the reenforcement at a proper predetermined position so that it will be imbedded a proper distance in the concrete forming the final road structure. As a general thing, however, the brackets 19 may be dispensed with 100 and the base layer of concrete relied upon to reinforce the concrete properly.

In Figure 6 the reenforcement dispensing machine is a self-contained construction. In this instance the carrier 2^a is adapted to be driven by its own motor 20 and has a winding drum 21 with which the pull cable 22, for pulling the reinforcement sections to position on the subgrade, is attached.

In Figure 7 a carrier 2^b is illustrated as being supplied with supporting standards 23 slotted to receive the supporting shaft 24 by which a bale of reenforcing is to be carried. The reenforcing 10^a is fed from the bale to the straightening rolls 25, and then between knives 26 to the base layer of concrete on the road. An operating cable 27 is connected with the upper knife 26 and with a motor driven part of the machine, not illustrated, to operate the knives to cut the reenforcing with a shearing action. In this construction I use a suitable pull cable 28 for unreeling the reenforcing from the bale 10^a, and pulling the same into position as well as thru the space between the straightening rolls 25. Obviously the bales of reenforcing designated 10^a may be lifted by the boom B of the machine A by simply engaging suspension cables with the ends of the shaft 24 and with the hooks 17. In 130

this way, the boom B is utilized readily for handling the heavy bale of reenforcing, in the same way it handles the reenforcing when disposed in a large quantity of superposed sheets or sections.

Whereas several men are now required to handle the heavy sections of metal reinforcement as they are laid down upon the road, and furthermore the reenforcement is scattered over quite a little area and has to be handled several times, the present machine offers the advantage of eliminating a very large percentage of the difficulty experienced under the present methods. In fact, a single man can practically attend to the handling of the reenforcement and by no means will the operation require all of his time.

Having thus described my invention, what I claim as new and desire to obtain by Letters Patent, is:

1. A machine of the class described comprising a carrier adapted to travel over a road bed, a support upon said carrier for a quantity of reenforcing material so that the latter may be dispensed for use in the road construction, a motor, and equipment operable from the motor and attachable to the reenforcement for pulling the latter into place upon the portion of the road where it is to be used.

2. A construction substantially as claimed in claim 1 wherein the power means comprises a power driven winding drum, a cable adapted to wind on said drum, and means for connecting said cable with the reenforcing material upon the carrier.

3. In combination, a paving machine comprising a motor propelled support, boom and bucket mechanism thereon, a carrier to support reenforcing material, means on said motor propelled support adapted to be connected with said reenforcing material on the carrier to pull said material into place over the concrete to be reenforced and beneath

the bucket of the boom and bucket mechanism.

4. A construction substantially as claimed in claim 1 combined with means for transferring the support upon the carrier to said carrier from a place at which the support and the reenforcing thereon may be picked up, the last mentioned means constituting a distributor.

5. In combination, a power driven machine adapted to travel over a subgrade of the road to be laid, a carrier adapted to be propelled by said power machine and a support for a quantity of metal reenforcing adapted to be received by said carrier, and a concrete distributor on said power machine adapted to lift said support from a place where it may be picked up, and transfer the same with the reenforcement thereon to a proper place on the carrier.

6. A machine substantially as claimed in claim 1, combined with equipment on the boom for hoisting a supply quantity of reenforcing material to position on the carrier therefor, and means for operating the boom for the last named purpose.

7. In a machine of the class described, a portable support, means for supporting concrete reenforcing in a quantity upon the support, and means to pull the reenforcing in place over a road bed as the support travels thereover, and to cut the reenforcing in suitable lengths for deposit upon concrete on the road.

8. In a machine of the class described, a portable support, means for supporting concrete reenforcing in a quantity upon the support, means to pull the reenforcing in place over a road bed as the support travels thereover, straighten it as it is so pulled, and means to cut the reenforcing into suitable lengths.

In testimony whereof I affix my signature.

JOHN F. ROBB.
